US0D1058666S

(12) **United States Design Patent** (10) **Patent No.:** **US D1,058,666 S**
(45) **Date of Patent:** **** Jan. 21, 2025**

(54) **RING BINDER MECHANISM**

(71) Applicant: **Youzhong Zhang**, Dongguan (CN)

(72) Inventor: **Youzhong Zhang**, Dongguan (CN)

(**) Term: **15 Years**

(21) Appl. No.: **29/888,056**

(22) Filed: **Mar. 28, 2023**

(30) **Foreign Application Priority Data**

Nov. 30, 2022 (CN) 202230800350.1

(51) **LOC (15) Cl.** **19-04**

(57) **CLAIM**

The ornamental design for a ring binder mechanism, as shown and described.

DESCRIPTION

FIG. 1 is a front perspective view of a ring binder mechanism showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines depict portions of the ring binder mechanism that form no part of the claimed design.

1 Claim, 8 Drawing Sheets
